Specification for Design.

Patented Oct. 2, 1917.

Application filed March 14, 1916. Serial No. 84,231. Term of patent 7 years.

To all whom it may concern:

Be it known that I, JOHN I. WARNER, a citizen of the United States, residing at Kansas City, in the county of Jackson and State of Missouri, have invented a new, original and ornamental Design for a Soft-Collar Retainer, of which the following is a specification, reference being had to the accompanying drawing, forming part thereof.

The figure is a perspective view of a soft collar retainer, showing my new design, for

connecting the loose front ends of the turn-down portions of the collar back of the tie.

I claim:

The ornamental design for a soft collar retainer, as shown.

In witness whereof, I have affixed my signature in the presence of two witnesses.

JOHN I. WARNER.
